UNITED STATES PATENT OFFICE

CHARLES T. KNIPP, OF URBANA, ILLINOIS, ASSIGNOR TO W. M. WELCH MANUFACTURING CO., OF CHICAGO, ILLINOIS, A CORPORATION OF ILLINOIS

CONDENSATION PUMP

Application filed October 13, 1930. Serial No. 488,312.

The present invention relates to a condensation pump and has particularly to do with a method and means of cooling employed therein and in the arrangement and structure 5 of the several elements thereof.

The effectiveness of a vapor pump is due in the greatest measure to the efficiency of its condensing element. It was with this idea in mind that the present construction 10 was developed.

The primary object of the present invention is an improved condensing element. The secondary object of the invention is an 15 improved arrangement of parts for the purpose of increasing the efficiency of the condensing element. Another object of the invention is an improved design for a condensation pump and its elements.

Other and additional objects of the invention 20 include novelties in the arrangement of the several elements of the pump and in the details of such parts.

These objects, and such other objects as hereinafter appear, are obtained by the novel 25 construction, unique arrangement and improved combination of elements in the two forms of invention herein illustrated and described, the drawing appended hereto and hereby made a part of this specification, illustrating the present invention as applied 30 to a single stage condensation pump and also as applied to a double stage condensation pump.

In the drawing—

35 Figure 1 is a longitudinal section through a single stage pump embodying the subject matter of the present invention;

Figure 2 is a similar view of a double stage 40 pump also embodying the invention.

Like reference characters are used to designate similar parts in the drawing and in the description of the invention hereinafter given.

45 Condensation pumps, in order to provide the vacuum for which they are designed, must always be used in conjunction with primary or, as they are called, "backing" pumps. Such backing pumps may be used in one or 50 two or more stages. In the present specifi-

cation such primary pump or pumps will always be known as the "backing" pump.

In both forms of the condensation pumps referred to herein, there is an external envelope ordinarily circular in cross section, 55 with a body 10 which terminates in an enlarged bottom section 11, in which a suitable liquid of low vapor tension is deposited and contained while in the liquid state. A small "seal-off" tube 9 is provided on one side of 60 the bottom section 11 to provide the means for cleaning the pump or changing the liquid used.

Adjacent to the top of the body 10 is a 65 projecting elbow 12 integral with or secured to body 10. Said elbow has a beaded or collar section 13 adjacent the end of the bent section thereof. Said elbow continues into the form of a tubular portion 14 of relatively 70 large cross section and to which some form of tube is connected by a vacuum-tight joint, dependent upon the material used, such tube leading to the vessel which is to be exhausted. Such connective member is not shown but extends to the vessel under exhaustion and 75 which is being degassed, which vessel also is not shown in the drawing.

The upper section of the body 10 is constricted at 18 to provide section 19 of smaller 80 diameter than body 10 and having three nipples, one (20) adjacent to the body 10, another (21) projecting vertically upright at one side of said section 19, and a third (22) intermediate the other two (20 and 21). Tubes 20 and 22 are designed to be connected 85 to a water supply system for cooling the condensation pump in a manner to be described later. Tube 21 serves to connect this condensation pump with the "backing" pump 90 already referred to.

Within the body 10, there is inserted beneath the elbow 12 an internal tubular envelope 23 arranged concentrically with the wall of body 10, but away therefrom. The lower end of said internal envelope is constricted and bent to form a U-shaped tube 24. Said U-shaped tube serves not only as a discharge tube for condensed liquid through the spout 25, which is turned upwardly, but also 95 as a liquid seal to prevent the vapor arising 100

from the boiling liquid in the lower part of the chamber 11 from passing upwardly into the internal envelope 23 through the opening 25. Internal envelope 23 is held in position 5 by suitably positioned spacer members 26, one only of which is shown.

Depending into the mouth of said internal envelope 23 and concentric with it is a short cylindrical member 27, with an upper funnel-shaped section 29 coinciding with and sealed to the wall of the external envelope 10. This cylindrical member serves as a deflecting collar for the vapor as it rises from the boiling liquid in the bottom of section 11, said vapor being deflected downward through the annular passage 30 between the external wall of member 27 and the internal wall of member 23.

Concentrically arranged with the external envelope 10, the internal envelope 23, and the deflecting collar 27, and inside all of them is a water-cooled condensing element 31 which comprises a unit having an external wall 32 which wall is generally cylindrical and which 20 forms with the internal wall of deflecting collar 27 a passage 33 of annular configuration therebetween.

Said cooling member 31 at its top 34 has its external wall flared and sealed to the material of the external envelope 10 at the constricted section 18. There is also provided at the lower end of said member 31 an extension of wall 32 which is inwardly turned to meet an inside wall 35 so as to form with 30 said inside wall 35 an annular chamber of irregular configuration which extends upwardly in the shape of a narrow tube-like open section or passage 36 elbowed at 37 and 38.

40 Said passage 36 extends through the condensing element 31 from the open bottom of the element to the top thereof, the passage terminating at the lower end of the nipple 21 to which the material of the internal wall 35 of said condenser member 31 is joined so that there may be a flow of gas upwardly 45 through the condensation pump being described to the backing pump, not shown, but suitably connected to said nipple 21.

50 Depending into said condenser member 31 is an elbowed tubular member 39, the upper end 40 of which is sealed to nipple 22. The lower end 41 of said tube 39 is open to provide for the discharge of a cooling medium into the condenser 31, such cooling medium being admitted through nipple 22.

By sealing the tube 39 and the internal wall 35 of the condenser member to the external envelope 10 at the points where nipples 22 and 21 are respectively joined to said external envelope the chamber 19 is completed, and is sealed off from the remainder of the pump. It is evident, therefore, that condenser member 31 through its inlet nipple 22, its outlet nipple 20, and its general con-

struction furnishes the means of conducting into and out of the center of the condensation pump a body of cooling water or other medium which may be kept in continuous motion so that the outer walls of the member 31 may always be sufficiently cooler than the vapor passing around it to condense the latter and thus assist in the operation of the pump.

Briefly stated the operation of the pump 75 is as follows: Mercury or any other suitable liquid of low vapor tension is deposited in the lower section 11 of external envelope 10 and the proper stream of water or other cooling medium is started through the condenser 80 31. A vacuum-tight joint has already been made between the vessel to be exhausted, not shown, and the elbowed section 12 and a connection made with the backing pump at nipple 21.

When the backing pump has provided in the system a reduced pressure (this may be as high as .2 or .3 or as low, say, as .03 millimeter of mercury), the source of heat for vaporizing the liquid, either an electrical heater 85 or any other suitable source, may be started.

Under the reduced pressure produced and maintained by the backing pump in the system, this liquid will boil easily and its vapor will soon rise within the external envelope 10 and will be deflected by the deflecting collar 27 so as to shoot downward with high velocity through the annular space 30 between collar 27 and the internal envelope 23. The particles of this vapor mingle with the air or other gas in and below the annular space 30 and bombard the molecules of such gas, accelerating their movement downward 90 into the lower part of internal envelope 23 where they are caught by the sucking action 95 of the backing pump and eliminated through passage 36 and nipple 21.

At the same time, the vapor comes in contact with the condenser 31, and condenses on the cool walls thereof and drops down 100 out of the way through discharge neck 24 and outlet 25. The high velocity of this vapor as it passes down the annular space 30 causes a reduced pressure in its wake 105 and thus hastens the movement of air or gas from the vessel being exhausted, bringing the vacuum in such vessel down to a very low point in an incredibly short time.

In the form of the invention shown in Figure 2, called a two-stage condensation pump, the structure is identical with that shown in Figure 1, except in respect to the internal envelope 23 which provides the main passage for vapor about the cooling member 31. Each of the parts found in Figure 2, which also appear in Figure 1, are given the same ordinal as in Figure 1, except that 110 100 has been added thereto.

Referring now to the changes in the internal envelope 23 in order to make the con-

densation pump a two-stage pump, it will be noticed in Figure 2 that the lower section of member 123 retains the U-tube 124 and the discharge opening 125 except that both 5 are disposed at the side rather than in the center of member 123. In addition, however, the bottom of member 123 is provided with an opening 150 which may be formed by the inturning of material 151 or by adding 10 an inverted funnel-shaped section sealed to the lower edge of the opening 150 and projecting upwardly a short distance into passage 136 leading to nipple 121 and the backing pump, not shown. Said section 151 has 15 a cylindrical top section terminating in aperture 152, said cylindrical section beginning at point 153. Between section 151 and the condensing elements is a passage 154.

Therefore, in the operation of a two-stage 20 condensation pump, as illustrated, the vapor formed in the reservoir 111 not only passes up between the internal envelope 123 and external envelope 110 so as to strike the deflecting collar 27 to be projected into the internal envelope from above, but also rises 25 rapidly from the body of the liquid in section 111 and shoots through the opening 150 into passage 136. In doing so, it not only accelerates the particles of air or gas being conveyed up passage 136 by the suction of the 30 backing pump but materially assists the backing pump in providing a reduced pressure to draw other particles of air or gas which have been accelerated toward the bottom of internal envelope 123 through the 35 annular space 130.

It will be seen that these two sources of bombardment can never interfere with each other because of orifice 152 extending up into 40 tube 136. Therefore, this new passage provided a second stage in the production of the vacuum and thereby increases the efficiency of the pump action. Of course, as the vapor of the volatile liquid passes up tube 45 136 it meets the internal walls of cooling member 131, condenses on these walls, and passes down them to drop back into chamber 111 through U-tube 124 and opening 125 without interfering with the stream of 50 vapor and air particles going up tube 136.

I claim:

1. In a condensation pump comprising an internal cooling system wholly within the other sections of the pump, an external envelope 55 adapted to telescope over said cooling system from below, and a deflecting collar sealed to said external envelope and adjacent said cooling system intermediate its length for directing rapidly moving vapor into the 60 path of air or gas coming from the vessel to be exhausted.

2. In a condensation pump, an external envelope, a deflecting collar attached to said envelope, an internal envelope concentric 65 with said external envelope and said deflect-

ing collar and so arranged that vapor may flow forwardly only in a path therebetween, an internal condenser telescoping into said envelopes, said deflecting collar being arranged to change the direction of the flow of 70 the vapor through one hundred and eighty degrees, and means for causing molecules of air and gas from the vessel to be exhausted to join with said vapor and travel therewith along said condenser. 75

3. A condensation pump comprising an external envelope, an internal envelope suspended therein and spaced from said external envelope, said internal envelope terminating in a gooseneck spout to discharge condensed 80 vapor, a condenser concentric with and within said inner envelope, there being a gas passage within said condenser comprising an exit tube for said pump, and a deflecting collar dividing said external envelope into 85 sections and having a skirt extending between said condenser and said internal envelope to reverse the direction of the flow of vapor in said pump and to direct the vapor downwardly about said condenser. 90

4. A condensation pump comprising an external envelope, an internal envelope suspended therein and spaced from said external envelope, said internal envelope terminating in a gooseneck spout to discharge condensed 95 vapor, a condenser concentric with and within said internal envelope, there being a gas passage within said condenser forming an exit tube for said pump, means for causing the vapor to flow downwardly about 100 said condenser, and means for causing a cooling media to flow upwardly from the bottom of said condenser.

5. A condensation pump comprising an external envelope, an internal envelope suspended therein and spaced from said external envelope, said internal envelope having a tubular passage vertically therethrough and terminating in a gooseneck spout to discharge condensed vapor, a condenser concentric with and within said envelopes, there being a gas passage within said condenser to provide an exhaust air or gas conduit through said pump, and a deflecting collar dividing said external envelope into sections 110 and having a skirt extending between said condenser and said inner envelope, said collar reversing the flow of vapor in said pump and causing the downwardly flowing vapor to surround said condenser. 115

6. A condensation pump comprising an outer envelope providing a generating chamber, an internal envelope, and a deflecting collar, said envelopes and collar being concentrically arranged and said deflecting collar being sealed at the periphery of its upper end to said external envelope, said envelopes and collar being so disposed that mercury or other vapor rising from said generating chamber is in contact with and restrained by 125 130

said external envelope until it strikes said deflecting collar, the vapor being turned thereby so as to take a parallel but diametrically opposite direction without interference 6 with the original stream of vapor particles.

7. In a condensation pump, an external envelope providing a generating chamber, an internal envelope, and a deflecting collar attached to said external envelope at its upper 10 end and extending downwardly into said internal envelope, said collar being in annular form with walls parallel to said external envelope, said envelopes and collar being so disposed as to cause a reversal in the flow of 15 the vapor in parallel streams, the upper end of said internal envelope forming with the deflecting collar an annular aperture through which the rapidly moving stream of vapor particles is projected downward by means 20 of its impingement against said deflecting collar.

8. In a condensation pump, an external envelope providing a generating chamber, a deflecting collar, and an internal envelope 25 suspended between said external envelope and said deflecting collar, said internal envelope terminating at its lower end in a gooseneck spout which serves to discharge condensed vapor into said generating chamber and at the 30 same time preventing vapor rising from said generating chamber from escaping from said outer envelope except through an annular passage between said external and internal envelopes.

35 9. A condensation pump having an intake tube and comprising an external envelope providing a generating chamber at its lower end and having a chamber at its upper end into which said intake tube empties, a 40 deflecting collar, an internal envelope having at its lower end a goose-necked tube, and a condenser having a passageway therethrough to provide an exhaust exit for air or gas from said pump, said envelopes, collar and condenser being concentrically disposed, there 45 being an annular passage between said deflecting collar and said condenser providing means of communication with said chamber in the upper part of said external envelope and in turn with the intake tube, so that air 50 is drawn into said pump by the suction produced by a downward rush of vapor from said deflecting collar, such air commingling with the vapor to be carried to the lower 55 extremity of said condenser where it is removed by suction produced by a backing pump, the vapor in said pump being condensed on the walls of the condenser on its way down and dropping into the lower portion 60 of the internal envelope to be conveyed through said goose-neck shaped tube to the generating chamber.

65 10. A condensation pump comprising an outer envelope forming a generating chamber, a deflecting collar thereon, an inner en-

velope concentric with said outer envelope and said collar, and a cooling chamber in which a cooling medium is constantly circulating and through which there is a central passageway, and in which vapor from said generating chamber rises vertically in said outer envelope to said deflecting collar, is turned through 180 degrees by the latter, shoots with high velocity downward through an annular space between said deflecting collar and said internal envelope, and by virtue of the high velocity drags with it air from the vessel to be exhausted, the vapor at the same time coming in contact with said cooling chamber in which water is continuously circulating, condensing on the walls thereof and dropping out of the way, leaving the air particles to be caught by a suction produced by a backing pump and carried vertically upward through the passage in the center of 75 said condenser, the passage in the center of said condenser providing an exhaust exit for air or gas from said pump.

80 11. In a condensation pump, an external envelope, a backing pump in connection therewith, and a deflecting collar attached to said external envelope and so disposed in the path of heated vapor in said envelope as to change the direction of flow of said heated vapor through 180 degrees without developing a back pressure, said vapor being thus turned with high velocity toward the bottom of the envelope and into the path of the suction of said backing pump.

85 12. A condensation pump of a two-stage type, and comprising an outer envelope forming a generating chamber, a deflecting collar in said envelope, an internal envelope the upper section of which is concentric with said outer envelope and said collar, said inner envelope extending above and outside the lower rim of said collar and having a funnel-like opening through the center thereof and a goose-neck drip tube from the lower end thereof, and a condenser circular in configuration and having a central passage therethrough to provide an exit tube for exhaust air or gas and telescoping into said collar and said inner envelope from above, said condenser being concentrically arranged within said envelopes and said collar, such vapor being adapted to flow through the center of said inner envelope and on the exterior thereof to be condensed on the outer or inner wall of said condenser, the condensed vapor flowing back into the generating chamber by way of said goose-neck tube, the funnel-like tube of said internal envelope being alongside of but separated from said gooseneck tube and being disposed to admit and direct a portion of the vapor rising from said generating chamber directly into the exhaust tube in the center of said condenser, such vapor forming an independent source of bombard- 90

ment of the air and gas as a second stage in the operation of said pump.

13. In a condensation pump, an external envelope, an internal condenser having a passageway therethrough, and a deflecting collar attached to said external envelope and so disposed in the path of the heated vapor as to change the direction of such heated vapor through one hundred eighty degrees without developing a back pressure and to spread such vapor into a thin film moving toward the bottom of the pump around said condenser and into the path of the suction of a backing pump through the passageway in said condenser and thence upward through the passageway in said condenser.

14. A condensation pump comprising an external envelope, an internal envelope suspended therein and spaced from said external envelope, said internal envelope terminating in a gooseneck spout to discharge condensed vapor, a condenser concentric with and within said envelopes, there being a gas passage within said condenser to provide an exhaust air or gas conduit through said pump, and a deflecting collar dividing said external envelope into sections and having a skirt extending between said condenser and said inner envelope, said collar reversing the flow of vapor in said pump and causing the downwardly flowing vapor to surround said condenser.
